[57] CLAIM

The ornamental design for a vehicle sideskirt set, as shown and described.

DESCRIPTION

FIG. 1 is a perspective view of one of the sideskirts of the vehicle sideskirt set showing our new design for mounting on the left side of an automobile;

FIG. 2 is an enlarged front view thereof;

FIG. 3 is an enlarged left side view thereof;

FIG. 4 is an enlarged right side view thereof;

FIG. 5 is an enlarged bottom view thereof;

FIG. 6 is an enlarged top view thereof;

FIG. 7 is an enlarged rear view thereof;

FIG. 8 is a perspective view of one of the sideskirts of the vehicle sideskirt set showing our new design for mounting on the right side of an automobile;

FIG. 9 is an enlarged front view thereof;

FIG. 10 is an enlarged left side view thereof;

FIG. 11 is an enlarged right side view thereof;

FIG. 12 is an enlarged bottom view thereof;

FIG. 13 is an enlarged top view thereof; and,

FIG. 14 is an enlarged rear view thereof.

The broken line showing of environment is for illustrative purposes only and forms no part of the claimed design.
